UNITED STATES PATENT OFFICE.

CHARLES L. GOODRUM, OF NEW YORK, N. Y., ASSIGNOR, BY MESNE ASSIGNMENTS, TO
WESTERN ELECTRIC COMPANY, INCORPORATED, A CORPORATION OF NEW YORK.

TELEPHONE SIGNALING SYSTEM.

1,200,829.

Specification of Letters Patent. Patented Oct. 10, 1916.

Application filed November 7, 1914. Serial No. 870,806.

To all whom it may concern:

Be it known that I, CHARLES L. GOODRUM, a citizen of the United States, residing at New York, in the county of New York and State of New York, have invented certain new and useful Improvements in Telephone Signaling Systems, of which the following is a full, clear, concise, and exact description.

This invention relates to a signaling system, and more particularly to a system for ringing on a two-wire automatic telephone system. Its object is to control the application of ringing current to the called subscriber's line by means of a switch or key which can be readily controlled by the calling subscriber in the transmission of code ringing impulses.

A further object resides in means to prevent the application of ringing current to the called subscriber's line when the calling subscriber hangs up his receiver.

With the above object in view, the application of ringing current to the called party's line is under the control of a slow-acting ringing relay, the circuit of which is controlled by a second slow-acting relay which in turn is controlled by a slow-acting release relay, whose circuit in turn is under control of a line relay. The circuit of the line relay is controlled by an interrupter actuated by the calling party. The calling party may, therefore, by operating his interrupter, cause the line relay to vibrate and thereby apply ringing current to the called party's line.

The several features of the invention may be more readily understood by reference to the accompanying drawing which is a diagram of so much of a two-wire automatic telephone system as is deemed necessary to an understanding of the invention.

The calling subscriber's station A and the called subscriber's station B may be connected to each other in the usual well-known manner, such connection being under the control of the dial 1 at the station of the calling subscriber. By lifting his receiver and actuating the dial, the called subscriber controls the operation of the finder 2 and the connector 3, thereby connecting the two limbs 4 and 5 of the calling subscriber's line with the limbs 6 and 7 of the called subscriber's line. The application of ringing current to the called line is dependent upon the vibration of a line relay 8, the circuit of

which may be traced as follows: from the grounded battery 9, through one winding 10 of the line relay 8, the limb 5 of the telephone line, telephone hook 11, the interrupter dial 1, the other limb 4 of the telephone line, winding 12 of the relay 8, to ground. After the calling party has operated the dial to select the line wanted, he may give it another turn, thus sending a series of impulses which causes the relay 8 to vibrate and thereby to cause ringing current to be applied to the line of the called party in the manner to be hereinafter described. The impulse transmitter may be satisfactorily used for ringing purposes when the office contains no party lines on which code ringing is essential. However, when code ringing is desirable, the use of the impulse transmitter is unsatisfactory, whereas a key of the push button type can be used to the very best advantage. A key of this type makes it possible for the subscriber to properly control the long and short rings ordinarily used in code ringing.

The relay 8 has a front contact 13 and a back contact 14. When said relay is energized, thereby closing its front contact 13, a circuit is closed for a slow-acting relay 15 as follows: from ground, through contact 13, relay 15, to one pole of the grounded battery 9. This causes the relay 15 to close its contact 16. Relay 15 being of the slow release type, maintains its contact 16 closed during the time that the line relay 8 is vibrating. The contact 16 is in the circuit of a second slow-acting relay 17, the circuit of which may be traced as follows: from grounded battery 9, through relay 17, contact 16, contact 14, closed in the released position of the relay 8, to ground. Relay 17 being likewise of the slow release type, maintains its contact 18 closed during the time the line relay 8 is vibrating. The contact 18 is in the circuit of a slow-acting ringing relay 19, the circuit of which may be traced as follows: from the grounded battery 9, through relay 19, contact 18, contact 13, closed in the actuated position of the relay 8, to ground. The relay 19 controls the application of ringing current to the called line, the circuit therefor being traced as follows: from the generator 20, through contact 21 of the ringing relay 19, one limb 6 of the called party's line, the bell 22, the other limb 7 of the called party's telephone line, 110

contact 23 of the ringing relay 19 to ground. Since the relay 17 is of the slow release type, its contact 18 remains closed during the vibration of the line relay 8, and since the 5 ringing relay 19 is of the slow release type, its contacts 21 and 23 likewise remain closed during the vibration of the line relay 8. Therefore, when the subscriber, by means of an interrupter, sends a series of impulses 10 over the line 4-5, he thereby causes ringing current to be impressed upon the line 6-7.

As hereinbefore stated, the subscriber's dial 1 may be used as an interrupter for causing the vibration of the line relay 8. 15 However, in certain cases it is preferable to employ another and independent interrupter for this purpose. In the preferred form of this invention, therefore, an electromagnetically actuated interrupter is provided, such 20 interrupter comprising the slow-acting electromagnet 24 and its contact 25 which are in series with one limb of the calling subscriber's telephone line. This electromagnetically actuated interrupter is normally 25 short-circuited by a switch 26 which is adapted to be manually operated by the calling subscriber, as, for example, by the actuation of a push-button 27. It thus appears that the calling subscriber by pressing 30 upon the button 27 removes the short-circuit from the electromagnetically actuated interrupter, and the circuit is, during such operation of the switch 26, opened and closed at contact 25, thereby applying intermittent 35 current to the relay 8, and causing the application of ringing current to the line of the called party in the manner hereinbefore described. It will be noted that so long as the button 27 is actuated, ringing current is 40 applied to the called line. The electromagnetically actuated interrupter, therefore, provides a convenient means for code ringing.

This invention provides a simple arrangement of circuits and apparatus for placing the ringing of the called subscriber under the direct control of the calling subscriber. It will be noted that the circuit arrangements are such that when the calling subscriber is connected to the line it requires a make and break of the calling line circuit before ringing current is applied to the called subscriber's line. Thus when the calling subscriber is connected for service and line relay 8 is energized, the slow-acting relay 15 is also energized. An interruption of the line circuit causes the deenergization of the line relay 8 whereas the slow-acting relay 15 will remain energized and the circuit completed by the armature of the deenergized line relay and the armature of the energized slow-acting relay 15 will energize and operate the slow-acting relay 17. A subsequent closure of the line circuit will 60 then reenergize the line relay 8 and the relays 65

15 and 17 being slow-acting, will likewise be energized and a circuit will now be completed through the slow-acting ringing relay 19 by way of the armature of the slow-acting relay 17 and the front contact and 70 armature of the line relay 8.

The foregoing description will make it evident that a make and break of the circuit is absolutely essential before ringing current can be applied to a called subscriber's line. This is of considerable advantage 75 in preventing the application of ringing current to the calling subscriber's line when the subscriber has the receiver off the hook. Thus, in case it were possible to energize 80 the ringing relay by simply breaking the line circuit of the calling subscriber, then if the calling subscriber were to hang up his receiver before the called subscriber, the latter would receive the ringing current in 85 his receiver, due to the energization of the ringing relay. This would be a serious disadvantage, and the second slow-acting relay 17 was included in this circuit to overcome 90 this operating defect existing in previous 95 systems.

What is claimed is:

1. In a signaling system, the combination of a calling subscriber's line, a line relay controllable over said line, an impulse sending device operated by the calling subscriber for controlling said relay, a slow-acting relay under the control of said line relay, a second slow-acting relay under the control of 95 said first mentioned slow-acting relay and a ringing relay always under the joint control of said second slow-acting relay and a calling subscriber's substation apparatus.

2. In a signaling system, the combination of a line relay, an interrupter for causing said line relay to vibrate, a slow-acting relay having a circuit closed in the actuated position of said line relay, a second slow-acting relay having a circuit closed in the actuated position of said first-mentioned 100 slow-acting relay, and a ringing relay having a circuit closed in the actuated position of said second slow-acting relay.

3. In a signaling system, the combination of a calling subscriber's line, a line relay controllable over said line, an impulse sending device operated by the calling subscriber for controlling said relay, a slow-acting relay having a circuit including the front contact of said line relay, a second slow-acting relay having a circuit including the front contact of said first mentioned slow-acting relay and the back contact of said line relay, and a ringing relay having a circuit always 110 controlled by said second slow-acting relay and the calling subscriber's impulse sending device.

4. In a signaling system, the combination of a line relay, an interrupter for causing said relay to vibrate, a slow-acting relay 115

having a circuit including the front contact of said line relay, a second slow-acting relay having a circuit including the front contact of said first-mentioned slow-acting relay and the back contact of said line relay, and a ringing relay having a circuit including the front contacts of said line relay and said second slow-acting relay.

5. In a telephone signaling system, the combination with a telephone line, of a line relay, an electromagnetically actuated interrupter in one limb of the telephone line, a manually operated switch in shunt of said interrupter, a slow-acting relay under the control of said line relay, a second slow-acting relay under the control of said first-mentioned slow-acting relay, and a ringing relay under the control of said second slow-acting relay.

10 6. In a telephone signaling system, the combination with a telephone line, of a line relay, an electromagnetically actuated interrupter in one limb of the telephone line, a manually operated switch in shunt of said interrupter, a slow-acting relay having a circuit closed in the actuated position of said line relay, a second slow-acting relay having

a circuit closed in the actuated position of said first-mentioned slow-acting relay, and a ringing relay having a circuit closed in the 30 actuated position of said second slow-acting relay.

7. In a telephone signaling system, the combination with a telephone line, of a line relay, an electromagnetically actuated 35 interrupter in one limb of the telephone line, a manually operated switch in shunt of said interrupter, a slow-acting relay having a circuit including the front contact of said line relay, a second slow-acting relay having a 40 circuit including the front contact of said first-mentioned slow-acting relay and the back contact of said line relay, and a ringing relay having a circuit including the front contacts of said line relay and said second 45 slow-acting relay.

In witness whereof, I hereunto subscribe my name this 6th day of November A. D., 1914.

CHARLES L. GOODRUM.
